CLAIM

The ornamental design for a microscope, as shown and described.

DESCRIPTION

FIG. 1 is a top, front, and right side perspective view of a microscope, showing my new design;

FIG. 2 is a bottom, rear, and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion labeled 9 in FIG. 1;

FIG. 10 is an enlarged view of a portion labeled 10 in FIG. 1; and,

FIG. 11 is an enlarged view of a portion labeled 11 in FIG. 2.

The broken lines in the drawings depict portions of the microscope that form no part of the claimed design. The dash dot dash lines in FIG. 1, FIG. 2, FIG. 9, FIG. 10 and FIG. 11 are for the purpose of depicting the boundary of the enlarged view and form no part of the claim.
